(57) **CLAIM**

The ornamental design for seat, as shown and described.

DESCRIPTION

FIG. 1 is a perspective view taken from the top, front and left side of a seat embodying my new design;

FIG. 2 is a front elevational view thereof, the right side, left side and rear elevational views being the mirror images thereof;

FIG. 3 is a top plan view thereof;

FIG. 4 is a bottom plan view thereof;

FIG. 5 is a perspective view taken from the top, front and left side of a second embodiment of my new design wherein the difference is substantially a matter of length.

FIG. 6 is a left side elevational view thereof, the right side elevational view being the mirror image thereof;

FIG. 7 is a front elevational view thereof, the rear elevational view being the mirror image thereof;

FIG. 8 is a top plan view thereof; and,

FIG. 9 is a bottom plan view thereof.
